UNITED STATES PATENT OFFICE.

LUDWIG STEINER, OF BERLIN, AND VICTOR GUTMANN, OF NUREMBERG, GERMANY,
ASSIGNORS, BY MESNE ASSIGNMENTS, TO WESTINGHOUSE ELECTRIC & MANUFACTURING COMPANY, A CORPORATION OF PENNSYLVANIA.

TOTALLY-INCLOSED ELECTRIC MACHINE.

Application filed January 23, 1926, Serial No. 83,144, and in Germany April 27, 1925.

Our invention relates to a totally inclosed electric machine and more particularly to a shaft sinking or mine pump motor.

Our invention consists of a further improvement of the electric machine described and claimed in a prior application Serial No. 67,653, filed Nov. 7, 1925, by Hans Richter and assigned to the Westinghouse Electric & Manufacturing Company. The stuffing box of the shaft and the casing or shell of this prior machine stand normally under liquid pressure. In the prior invention, the sealing of the machine casing is effected in such a manner that small quantities of liquid are allowed to penetrate into the casing, but a sump or collecting vessel is provided at the lower end of the machine casing for catching the liquid which has penetrated and in this sump or collecting vessel 20 a pump is located which ejects the liquid again from the casing.

It is not desirable to drive this sump pump permanently by the electric motor, as in said prior invention, because it would eject air 25 from the casing after all the liquid has been removed and would thus increase the difference of pressure at the stuffing box which is, of course, undesirable. For this reason, we have provided a coupling or clutch between 30 the pump and the electric motor, which is thrown into gear only when a certain quantity of liquid has collected in the collecting vessel or sump.

The construction or design of the coupling offers special difficulties in the present case. The machine forming the object of our invention is intended specially for borings in shaft sinking operations. It is of elongated and slender design and there is little room 40 for housing the coupling within its casing. Since the machine is expected to work under unfavorable service conditions sometimes for several weeks in a bore hole of great depth without any attendance whatever, it is necessary that the coupling should be of simple construction and capable of withstanding rough usage. Couplings with a device for throwing it in gear operated by a float, as proposed for other conditions of machines, 45 are for this reason quite unsuitable in the boring of shafts.

According to our invention, the problem is

solved by connecting the motor with the sump pump by a liquid friction coupling. Such couplings are known but have never before been employed for this purpose. According to our invention, the coupling is located in the sump in such manner that the liquid rises into it and couples the pump with the motor when the level of the liquid in the sump has attained a certain height and the liquid retires from the coupling and releases the pump from the motor when the level of the liquid has dropped below a critical level owing to the discharge of the liquid from the casing.

An embodiment of our invention is illustrated in the drawing affixed hereto, wherein

Fig. 1 is a view in longitudinal section of the complete mine or well pumping motor, 70 the main pump, which is normally located above the motor, having been omitted as forming no part of our present invention.

Fig. 2 is a detail view of the liquid friction coupling in partial vertical section on a larger scale, and

Fig. 3 is a fractional detail view of the coupling in horizontal section on a still larger scale.

Referring to Fig. 1, the motor M is provided in a casing having a sump or collecting vessel S in its lower part, wherein is located a sump pump P which is connected to the motor shaft by a liquid friction coupling K. The sump pump draws the liquid in through the bore 1 and discharges it from the casing at 4 by the pipe 2 in which a non-return valve is provided at 3. We prefer to utilize a sump pump with rolling pistons although, of course, any other suitable type may be employed.

The liquid friction coupling K has the following construction. Referring in particular to Fig. 2, it will be seen that upon the lower end 5 of the motor shaft is firmly mounted or keyed a collar 6 having a peripheral shell or cylindrical flange 7. The outer circumference of the shell 7 is provided with teeth 8, in the manner of a circular saw, and with a plurality of radial bores 9.

Upon the upper end of the sump pump shaft 10 is mounted a disc 11 so as to be incapable of rotation thereon. This disc 11

is integral with a cylindrical shell or flange 12 surrounding the shell 7 with a small clearance, and provided with teeth 13 upon its inner circumference, as indicated more clearly in Fig. 3.

The outer circumference of the shell 12 is provided with a closely fitting angular ring 14 which cooperates with the disc 11 and its shell 12 to provide an annular chamber which also embraces the larger portion of the collar 6. The hub of the collar 6 projects through a central opening 15 in the horizontal top part of the angular ring 14. The angular ring is secured in position at two diametrically opposite places by pins 16 which project through bores in the shell 12 and in the angular ring 14 and are held by, or are integral with, a semi-circular spring ring 17 located in a milled groove in a portion of the shell 12 which projects downwards over the outer circumference of the disc 11. The hub of the disc 11 is provided with a plurality of oblique bores 18. In the shell 12 and the angular ring 14 fine bores 19 are provided at diametrically opposite points of the circumference closely above, or in alignment with, the upper face of the disc 11.

The manner of operation of the device is as follows: As soon as the motor is immersed in the liquid within the bore hole the hydrostatic pressure of the column of liquid above it acts upon the packings surrounding the shaft of the motor M. Under the action of this pressure, liquid leaks slowly into the casing of the machine. In the absence of suitable provisions, the leaking would cease only when the air in the machine casing had been so strongly compressed that its pressure balanced the hydrostatic pressure of the liquid. This does not happen, however, because as soon as a certain quantity of liquid has collected in the sump, it is ejected again at a far quicker rate than that at which it has leaked into the casing. In this manner the initial state is restored again. The use of a coupling capable of disengagement prevents the pump from ejecting air also from the casing, which would increase the pressure difference acting at the packings, as above pointed out.

The liquid coupling operates in the following manner. The motor shaft 5, with the disc 6, is rotated continuously, as is also the main pump (not shown) which is located above the motor. The shaft 10 of the sump or auxiliary pump, with the disc 11, is ordinarily inoperative. If now the sump of the motor becomes filled with liquid, the level of the rising liquid first reaches the disc 11 at the outer mouths of the bores 18. When the liquid continues to rise, the bores 18 gradually becomes filled with liquid and finally the liquid enters the annular space between the shell 7 and the shell 12, partly

through the bores 18 and the clearance below the shell 7, and partly through the bores 19.

When the liquid has reached a certain level A—A, Fig. 1, in this space, the disc 11 is carried along by the shell 7. As soon as the disc 11 has attained a certain speed a large quantity of liquid is conveyed into the annular space between the two concentric shells or flanges 7 and 12 through the bores 75 9, owing to the centrifugal action of the liquid, and the space becomes completely filled up with liquid within the range of the teeth 8 and 13.

Although a certain slip occurs between the shafts 5 and 10, a torque is transmitted by the coupling which, provided the device is suitably proportioned, amply suffices to drive the sump or auxiliary pump. As a result of the action of the pump, the level 85 of the liquid in the sump is lowered. The liquid drops down to the lower mouth of the oblique bores 18 of the coupling, level B—B, Fig. 1. When no more liquid is drawn in through the said bores 18, the coupling is 90 drained through the smaller openings 19 and the shaft 10 of the sump pump again becomes inoperative.

Various modifications and changes may be made without departing from the spirit 95 and the scope of the invention, and we desire, therefore, that only such limitations shall be placed thereon as are imposed by the following claims when read in the light of the prior art.

We claim as our invention:

1. A totally inclosed electric motor for operating immersed in a liquid, with a sump within the casing for the liquid which has leaked into the casing, a pump for draining said sump, and a liquid friction coupling for detachably connecting the motor shaft with the shaft of said pump.

2. A totally inclosed electric motor for operating immersed in a liquid, with a sump within the casing for the liquid which has leaked into the casing, a pump for draining said sump, and a liquid friction coupling for detachably connecting the motor shaft with the shaft of said pump, said coupling being located in the sump in such a position that the liquid penetrates into it and couples the pump with the motor when the level of liquid in the sump has attained a certain height and drains out of said coupling and disengages the pump when the level of liquid has dropped below the critical level again.

3. An inclosed submersible motor having a sump in the bottom thereof, a sump pump for draining the sump of accumulations of liquid, and a liquid-level-responsive coupling for driving and disconnecting the sump pump from the motor shaft.

4. An inclosed submersible motor having

a sump in the bottom thereof, and a liquid-level-responsive pump mechanism in the sump for expelling the fluid contents of the sump only when a liquid has reached a predetermined range of levels therein.

5. An inclosed submersible motor having a sump in the bottom thereof, and pumping mechanism operative only on a liquid content and not on a gaseous content in the sump for expelling the liquid therefrom when it has reached a predetermined range of levels therein.

6. An inclosed submersible motor having a sump in the bottom thereof, a sump pump 15 for draining the sump of accumulations of liquid, and a coupling mechanism operative only on a liquid content and not on a gaseous content in the sump for coupling the sump pump to the motor shaft.

20 7. An inclosed submersible motor having a sump in the bottom thereof, a sump pump for draining the sump of accumulations of liquid, and a liquid-friction clutch device which engages the drainage pump to the motor shaft and drives it until the liquid suction breaks in the clutch device.

25 8. An inclosed submersible motor having a sump in the bottom thereof, a sump pump

for draining the sump of accumulations of liquid, and a liquid-level-responsive coupling for driving and disconnecting the sump pump from the motor shaft, said coupling being a liquid-friction clutch comprising a cup-shaped clutch member attached to one shaft and a male clutch member on another shaft, said clutch members having internally and externally directed teeth in closely spaced relation, whereby one clutch member is driven from the other only when a liquid is interposed therebetween.

30 9. An inclosed submersible motor having a sump in the bottom thereof, a sump pump for draining the sump of accumulations of liquid, and a liquid-level-responsive coupling for driving and disconnecting the sump pump from the motor shaft, said coupling being a device for transmitting torque in response to a liquid pressure developed in the coupling for driving said sump motor, the torque developed by gas pressure when the coupling is immersed in a gaseous medium being insufficient to drive said sump motor.
